UNITED STATES PATENT OFFICE.

ARTHUR E. FAHRMAN, OF ROCHESTER, MINNESOTA.

PERFORATING-MACHINE.

1,009,396.

Specification of Letters Patent. Patented Nov. 21, 1911.

Application filed June 3, 1911. Serial No. 631,164.

To all whom it may concern:

Be it known that I, ARTHUR E. FAHRMAN, a citizen of the United States, residing at Rochester, in the county of Olmsted and 5 State of Minnesota, have invented certain new and useful Improvements in Perforating Machines, of which the following is a specification.

This invention relates to improvements in 10 machines for perforating articles such as checks, and other papers and like articles, and has for one of its objects to simplify and improve the construction and increase the efficiency and utility of devices of this character.

Another object of the invention is to provide a device of this character which may be readily adjusted to checks or other papers of various sizes and which may be readily 20 adapted for perforating one or a number of superimposed sheets without structural change or detaching any of the parts.

Another object of the invention is to provide a device of this character wherein 25 means are provided for adjusting the platen or base-member to correspond with the perforating pins.

With these and other objects in view the invention consists in certain constructions, 30 arrangements and combinations of the parts that I shall hereinafter fully describe and claim.

For a full understanding of the invention reference is to be had to the following description and accompanying drawings, in 35 which:—

Figure 1 is a side elevation of the improved device partly in section. Fig. 2 is a plan view of the same partly in section. 40 Fig. 3 is a transverse section on the line 3—3 of Fig. 1. Fig. 4 is an enlarged perspective view of one of the combined stripper and guide plates.

Corresponding and like parts are referred 45 to in the following description and indicated in all the views of the accompanying drawings by the same reference characters.

The improved device comprises a base or 50 table 10 of any suitable material or any suitable size, the table being formed to correspond to the size of the sheets to be perforated. It is not desired, therefore, to limit the size of the table or other parts.

Rising from the base 10 at the ends are 55 standards 11 in which a main driving shaft

12 is mounted and provided with suitable means for imparting rotary movement thereto, as for instance, a belt pulley 13.

The perforating devices are connected to the shaft 12 and any required number of 60 these devices may be employed, but for the purpose of illustration three are shown and mounted and spaced at equal distances apart, but as all the perforating devices including the "platen" therefor are precisely alike, 65 the description of one will suffice for all.

Embodying in the base 10 at points corresponding to the positions of the perforating members are frames or socket devices represented as a whole at 14 and formed with 70 an oblong recess or seat in the upper side in which a plate 15 is mounted to slide. The socket member 14 is provided with a longitudinal slot 16, and extending through this slot and into a cavity 17 in the base 10 is 75 an arm 18 having a threaded aperture to receive a threaded rod 19. The rod extends through a suitable bearing in the base 10 and is provided at its outer end with a thumb wheel 20. The rod 19 is held from 80 longitudinal movement by any suitable means, for instance, by a stop collar 21 and a keeper 22, so that while the rod is free to be rotated it will not move longitudinally. By this means it will be obvious that by ro- 85 tating the rod 19 the plate 15 is adjusted in the socket of the plate 14. The plate 15 is provided with a plurality of perforations indicated conventionally at 23 and corresponding in size and distance apart with 90 the perforating pins of the improved device, as hereinafter explained.

Depending from the shaft 12 above each of the socket members 14 is a tubular guide 24, and slidable in each tubular guide is a 95 rod 25. The shaft 12 is likewise provided with a stop collar 26 for each of the guides 24 and each provided with a set-screw 27 to enable the collar to be adjusted to any desired extent and likewise rigidly coupled 100 to the shaft. At its lower end each rod is provided with a transverse head 28 from which the perforating pins 29 depend, the pins corresponding in size and distance apart with the apertures 23 of the "platen" 105 plate 15. Connected to the base 10 opposite each row of pins 29 is a guide plate 30 having perforations corresponding to the pins 29 and through which the pins move when the rod 25 is operated. The plate 30 thus 110

serves the two fold purpose of a guide for the pins and likewise as a stop-plate to prevent the paper or other article which is being perforated from being moved upwardly at the return stroke of the pins, as hereafter more fully explained.

Means are provided for actuating the rods 25, and an improved means for accomplishing this result is shown, and consists of a cam-wheel 31 mounted for rotation with the shaft 12 and provided with a cam-groove 32 in which a laterally extending offset 33 of the rod 25 operates. The guide 24 is provided with a longitudinal slot 34 through which the offset 33 extends and in which it moves vertically under the influence of the cam. By this simple arrangement it will be obvious that when the shaft 12 is rotated the cam 31 will, through the coaction of the offset 33 and the cam-grooves 32 impart a vibratory movement to the rods and cause the pins 29 to pass downwardly through the plate 30 and into the perforations of the "platen" plate 15, and "punching" apertures corresponding to the pins in any paper or other article which may be inserted between the plate 30 and the platen member 15. At the return stroke of the rods 25 the plate 30 will serve as a stop to prevent the paper or other article from being lifted from the table, as will be obvious, or to strip the paper from the pins.

Connected to the table 10 near one end is a gage-member 35 provided with an adjusting screw 36, while a similar gage 37 is located upon the table near the opposite end, and rendered adjustable by a clamp screw 38. The gage 35 extends transversely of the base 10, while the gage 37 extends longitudinally of the table. The gage plates thus serve as means for guiding and supporting the paper which is to be perforated, and may be readily adjusted to correspond to the size of the paper. As before stated, any required number of the perforating devices may be employed, but generally three will be used, as shown. The cams 31 are each provided with a set-screw 39 so that the cams may be adjusted longitudinally of the shaft and thus co-act with the stop collars 26 and their set-screws 27 to adjust the guides 24 longitudinally of the shaft when required. By this means all the different parts may be readily adjusted to cause them to operate in perfect unison.

The improved device may be constructed of any suitable material and of any suitable size to adapt it to the work required and may be adapted for use in banks, commercial houses, printing offices, or other localities, but is designed more particularly in the use of printing houses for the purpose of perforating sheets which are afterward bound in books such as checks, drafts, blank receipts, or orders and the like, and is capa-

ble of general application as an efficient perforating machine.

Having thus described the invention what is claimed as new is:—

1. In a device of the class described, a table, a plate having a plurality of apertures and supported upon said table, a shaft, a tubular guide depending from said shaft, a rod slidable in said guide, a plurality of pins carried by said rod and corresponding in number to and adapted to enter the perforations of said plate, and means operative by said shaft for reciprocating said rod to cause said pins to enter said apertures. 70 75

2. In a device of the class described, a table, a plate having a plurality of apertures and supported upon said table, means for adjusting said plate, a shaft, a tubular guide depending from said shaft, means for adjusting said guide upon said shaft, a rod slidable in said guide, a plurality of pins carried by said rod and corresponding in number to and adapted to enter the perforations of said plate, and means operative by said shaft for reciprocating said rod to cause said pins to enter said apertures. 80 85

3. In a device of the class described, a table, a plate having a plurality of apertures and supported upon said table, a guide supported upon said table and provided with apertures corresponding to the apertures of the plate, a shaft, a tubular guide depending from the shaft, a rod slidable in said guide, a plurality of pins carried by said rod and corresponding in number to and operating through the apertures of the guide and likewise corresponding to and adapted to enter the perforations of said plate, and means operative by said shaft and reciprocating said rod to cause the pins to enter 105 the apertures of said plate. 100 105

4. In a device of the class described, a table, a plate having a plurality of apertures and supported upon said table, a shaft, a tubular guide depending from said shaft 110 and provided with a longitudinal guide slot, a rod slidable in said guide and provided with an offset extending through said guide slot, a plurality of pins carried by said rod and corresponding in number to and adapted to enter the perforations of said plate, and a cam device connected to said shaft and engaging said offset and operating to reciprocate said rod to cause said pins to enter said apertures. 115 120

5. In a device of the class described, a table, a member having a socket cavity and carried by said table, a plate slidable in said socket and provided with a plurality of apertures spaced apart, means for adjusting said perforated plate in said socket, a rod having a plurality of pins corresponding in number to and adapted to enter the perforations of said plate, and means for reciprocating said rod and the pins carried thereby. 125 130

6. In a device of the class described, a table, a member having a socket cavity and carried by said table, a plate slideable in said socket and provided with a plurality of apertures spaced apart, means for adjusting said perforated plate in said socket, a guide supported upon said table and provided with perforations corresponding to the perforations of the plate, means for adjusting 10 the guide, a rod having a plurality of pins corresponding in number to the apertures

of the guide and of the plate and adapted to enter the perforations of said plate, and means for reciprocating said rod and the pins carried thereby. 15

In testimony whereof, I affix my signature in presence of two witnesses.

ARTHUR E. FAHRMAN. [L. S.]
